AUTOMOBILE ACCESSORY CONSOLE

Jack Nimetz, 9119 Manchester Road, Silver Spring, Md.,
and Benjamin B. Weitz, 7611 Maple Ave., Takoma Park, Md.

Filed Nov. 16, 1964, Ser. No. 82,626

Term of patent 7 years

(Cl. D14—6)

FIG. 1 is a perspective view of an automobile accessory console, showing our new design; with the broken line portions being included for illustrative purposes only.

FIG. 2 is a perspective view of the accessory console.

FIG. 3 is a sectional view of the accessory console.

We claim:

The ornamental design for an automobile accessory console, substantially as shown and described.
